UNITED STATES PATENT OFFICE

GIUSEPPE M. BELLANCA, OF WILMINGTON, DELAWARE

AIRPLANE CONSTRUCTION

Application filed November 27, 1928. Serial No. 322,126.

This invention relates to airplane construction and will be understood from the following description read in conjunction with the drawings, in which

5 Fig. 1 is a front view of an airplane constructed in accordance with my invention;

Fig. 2 is an alternative form of construction;

10 Fig. 3 is a detailed perspective side view of Fig. 1 with the outer covering of the wings removed;

Fig. 4 is a side view of Fig. 1;

Fig. 5 is a vertical section through part of Fig. 1 longitudinal to a wing;

Fig. 6 is a section through part of Fig. 1 transverse to a wing;

Fig. 7 is a top view showing a pin fitting adapted to connect the wing sections; and

Fig. 8 is a horizontal section through part of Fig. 1.

Referring specifically to Figs. 1 and 2, the construction which characterizes my invention may be applied to either a double bay job, as illustrated in Fig. 1, or to a job containing three or more bays, as illustrated in Fig. 2. The phrase bay as herein employed denotes the space vertically bounded by upper and lower wings and horizontally by two vertical struts, or a vertical strut and some other part of the plane, such as the fuselage or a strut-wing. In either event the lower wings are relatively shorter and I provide true wing portions extending diagonally outward and upward from the extremities of the lower wings to the upper wings, which portions are so formed as to simultaneously function as wings and brace members. These portions may meet the upper wings at any point, such as, for example, the tips, or preferably meet the upper wings at points intermediate between the fuselage and tip, thereby placing that part of the upper wing extending outwardly beyond the point of connection in cantilever and imparting a maximum of strength in proportion to weight. The wing portion so provided having the combined properties of a wing and a strut may be hereinafter briefly referred to as a strut-wing.

This strut-wing has at its inner extremity

a chord equal to that of the lower wing and preferably tapers with gradually diminishing chord as the upper wing is approached. The lower wing preferably has a chord substantially equal to the chord of the upper wing. In the preferred form of my invention the lower wing is relatively short, preferably not exceeding one-third of the length of the upper wing and has a cathedral, that is, it extends outwardly and downwardly from the fuselage. Such a wing may be hereinafter referred to as a stub wing. This stub wing may be constructed as a true cantilever structure so that vertical or nearly vertical struts connected adjacent the outer extremity of the lower wing and extending vertically or nearly so to meet the upper wing may be eliminated.

It will be apparent that the strut-wing may be constructed in accordance with accepted practice to carry stresses incidental to its function as a lifting member and must, in addition, be adapted to carry tensile and compressive stresses incidental to its function as a strut. The strut-wing may comprise only one longitudinal brace or strut surrounded by compression ribs, to which brace the compression ribs are attached. Preferably, however, the struts are in tandem, and I accomplish my purpose as illustrated in Fig. 3 by extending the forward and rearward beams 1 and 2 of the strut-wings 3 and carrying the said beams upwardly to join the forward and rearward beams 4 and 5 which are a part of the corresponding upper wing. The forward and rearward beams 1 and 2 in the strut-wing structure operate as struts or braces to preserve the spatial relationship between the upper and lower wings. The strut-wing is provided with the conventional compression ribs 6 or any alternative means for imparting the necessary backing to the air foil. These compression ribs are shown in perspective in Fig. 3. I may, of course, use only one strut extending from the stub wings to the upper wings and utilize this to carry the ribs which back the air foil, thereby making a true wing portion founded on the single strut mentioned, or I may employ more than the two struts illus-

trated in Fig. 3 as the foundation for a wing portion of this character. Alternatively I may employ two or more struts extending from each stub wing to the corresponding upper wing each of which struts carries a separate set of ribs and is the foundation of a distinct true wing portion. Such modifications shall be included in the meaning of the term strut-wing as herein employed.

5 As shown diagrammatically in Fig. 6, the forward and rearward beams 1 and 2 may be riveted securely to the forward and rearward beams 4 and 5. Alternatively, they may be fastened by hinges, or pin fittings, or in any other manner. The strut-wing may terminate at its lower end in the bulk-head 7 or may constitute a structural extension of the lower wing. The lower end of the strut-wing may be connected to the outer extremity of the lower wing in any suitable manner, for example, by means of a pin-fitting 8, Fig. 5, or alternatively solid construction may be employed. A top view of one form of pin-fitting appears in Fig. 7. As a matter of convenience, in the specific type of airplane shown in Fig. 1 the upper wings are composed of two sections which are also connected together by pin-fittings 10. The relative position of these pin-fittings and of the forward and rearward beams 1 and 2 is shown in Fig. 8.

It will, of course, be understood that the foregoing description of a specific embodiment of my invention is by way of illustration and not of limitation. It is my intention that the invention be limited only by the appended claims, or their equivalents, in which I have endeavored to claim broadly all inherent novelty.

40 I claim:

1. An airplane comprising a fuselage, upper wings extending directly from the sides of said fuselage, relatively shorter lower wings with a chord substantially equal to the chord of the upper wings extending directly from the sides of said fuselage, strut-wings extending outwardly and upwardly from the outer ends of said lower wings and connected to the said upper wings.
- 45 2. An airplane comprising a fuselage, upper wings extending directly from the sides of said fuselage, relatively shorter lower wings with a chord substantially equal to the chord of the upper wings extending directly from the sides of said fuselage, strut-wings extending outwardly and upwardly from the outer ends of said lower wings and connected to the said upper wings, which said upper wings extend in part outwardly beyond the points of connection of said strut-wings thereto.
- 50 3. An airplane comprising a fuselage, upper wings extending directly from the sides of said fuselage, relatively shorter lower wings extending outwardly and downwardly

directly from the sides of said fuselage, strut-wings extending outwardly and upwardly from the outer ends of said lower wings and connected to the said upper wings.

4. An airplane comprising a fuselage, upper wings extending directly from the sides of said fuselage, relatively shorter lower wings extending outwardly and downwardly directly from the sides of said fuselage, strut-wings extending outwardly and upwardly from the outer ends of said lower wings and connected to the said upper wings, which said upper wings extend in part outwardly beyond the point of connection of said strut-wings thereto. 75

5. An airplane comprising a fuselage, upper wings extending directly from the sides of said fuselage, relatively shorter lower wings extending outwardly and downwardly directly from the sides of said fuselage with a chord substantially equal to the chord of the upper wings, strut-wings extending outwardly and upwardly from the outer ends of said lower wings and connected to the said upper wings. 80

6. An airplane comprising a fuselage, upper wings extending directly from the sides of said fuselage, relatively shorter lower wings extending outwardly and downwardly directly from the sides of said fuselage with a chord substantially equal to the chord of the upper wings, strut-wings extending outwardly and upwardly from the outer ends of said lower wings and connected to the said upper wings. 85

In testimony whereof, I have signed my name to this specification this 15 day of November, 1928.

105 GUISEPPE M. BELLANCA.
